LOCK

Morris Falk, Leominster, Mass., assignor to Independent Lock Company, Fitchburg, Mass., a corporation of Massachusetts

Application November 26, 1937, Serial No. 176,409

7 Claims. (Cl. 292—359)

This invention relates to door closure fasteners, by which a latch bolt is retracted by turning the door knob or handle on either side of the door. The invention more particularly relates to locking devices for such closure fasteners so that by operating a lock lever or handle, usually provided on one side of the door, the door becomes locked and cannot be opened from the other side of the door. Such locking devices are most commonly provided on the inner side of bath room doors so that privacy may be assured by locking the device, although such locking devices—and the improvements of this invention—have many other uses.

As now commonly made, the door closure fasteners (by which is meant the latch bolt, door knobs and associated parts) are provided with locking means which are entirely independent of the closure, except that they may be provided on the same casing, and which locking means have a separate and independent bolt for locking the door. This construction of an independent locking bolt and mechanism necessarily increases the size of the composite casing, which is usually made in the form of a rectangular block of considerable size.

In installing this locking door closure, the free edge of the door must be cut or morticed to provide a rectangular opening for the closure block. This type of locking door closure fastening is consequently known in the trade as the "mortice" type closure. Where not provided with locking means, closure fasteners need not, and do not, have the large block casing, but comprise merely compact, usually cylindrically shaped parts which slip into small size bores or passages cut or drilled in the door. This type of closure is called "non-mortice".

One object of this invention is to provide a locking device for a door closure fastener of the non-mortice type, which will avoid the need of a large block casing and thus eliminate the need of cutting or mortising the door to receive the block. Closely allied to this object, is to provide such a locking device so that it may be installed in the place of present non-locking closures, whether of the mortice or non-mortice type, without the need of further cutting or mutilation of the door, existing clearances being sufficient (except perhaps, a simple drill hole, where the law requires a safety or emergency unlocking means, as will subsequently be fully described).

Another object is to provide a locking device for a door closure which is not independent thereof, i. e. which does not necessitate a second,

independent latch bolt, but which is intimately associated with the latch bolt of the closure fastener. This object contemplates a door closure fastener provided with a locking means which is of unitary construction.

From another aspect, the invention contemplates a door closure fastener and locking means which is also unitary in operation, so that, in grasping the knob or handle to retract the latch bolt of the closure fastener, the locking device may be simultaneously manipulated to unlock the door, and vice versa, in closing and locking the door, and to include simple and economical construction which makes installation possible quickly and facilely with any existing construction which may lack a locking device in the original installation.

Another object is to provide the unitary closure fastener and locking device with a safety means for unlocking the door from the other or outer side thereof.

For the attainment of the above objects and such other objects of my invention as shall hereinafter appear or be pointed out, I have shown one embodiment in the accompanying drawing, 25 wherein—

Figure 1 is an end view of a door in which is installed a non-mortice closure fastener provided with the locking device of this invention;

Figure 2 is a side view of the door and closure of Figure 1, with the door knob removed;

Figure 3 is a sectional view of the locking mechanism, taken on line 3—3 of Figure 1, with the knob spindle locked;

Figure 4 is the sectional view of Figure 3 with the spindle unlocked;

Figure 5 is a sectional view taken on a medial line through the door, on the line 5—5 of Figure 3.

The door (in which a closure fastener incorporating the novel locking device of this invention is installed) designated 10 in the figures, is provided with the usual cylindrical bore 9 running through the thickness of the door from side to side, through which clears the usual square spindle 18 of the closure fastener. The inner side of the door, which is the right side as viewed in Figures 1 and 5 (this side of the door being conveniently designated 10R) is provided with the usual rose plate or escutcheon plate 18, provided with a central opening 18a, Figure 5, for the right end of spindle 19. The right side of the door is considered as the "inner" side inasmuch as it will be assumed that this side of the door faces upon the bath room or other room 55

which it is desired to be locked from the inside for privacy or other reasons.

The rose plate 18 is secured to the side of the door by the usual screws 14, as shown in Figures 5 and 2. The outer or left side of the door, 10L, is provided with a similar rose plate 18'. To both ends of the spindle 19, projecting beyond the rose plates in the respective sides of the door, is secured, as by screws, shown in Figures 5 and 10 1, a handle or knob; the right knob, i. e. on the inside of the door, is designated 17 and the left or outer knob is designated 17'. As best seen in Figure 5, the inner ends of the door knobs are received in a recess 18r, provided therefor 15 in the rose plates 18 and 18'.

The door is further provided with the usual cylindrical passage 6, which extends from the free edge of the door, designated 107 in Figures 1 and 2, to the said cylindrical bore 9. Within 20 the cylindrical passage 6 slides the usual latch bolt 16 of the usual cam or wedge shaped end construction. The latch bolt 16 is operatively connected to the knob spindle 19 in the usual manner (not shown) so that the turning of the 25 door knobs, either the inner knob 17 or the outer knob 17', will retract the bolt, which, in addition, is provided with the usual spring (not shown) normally maintaining it in forward (to the left as viewed in Figure 2) position.

20 The cylindrical door passage 6 may be provided with a shell or lining 15, Figure 5, with which the latch bolt 16 is in sliding contact.

The structure thus far described is the conventional door closure, comprising essentially a 35 pair of door knobs and a latch bolt which is retracted by turning the knobs. It will be noted that the type of door closure illustrated is, in the nomenclature of the trade, the non-mortice type, by which is meant that a large rectangular 40 shaped opening need not be cut or morticed into the free edge of the door to receive the rectangular block usually required in mortice type closures.

This rather large size block and the consequential morticing of the door are required in the 45 type of closures known as "mortice" because of the provision of a locking means associated with the door closure. Where the locking provision is omitted, the non-mortice closure may be used; heretofore, where the locking feature was required the mortice closure must be used or unsafe and hazardous locking means employed there-with which, in emergencies, are inaccessible for opening without ruining the door structure.

This invention contemplates in its preferred 55 form, a non-mortice type door closure which is provided with a locking means and which consequently may be readily installed in a door in the manner in which the usual non-locking, non-mortice closures are at present installed, i. e. 60 without the need of cutting or morticing a large rectangular opening in the edge of the door. The door need have merely the usual cylindrical bore 9 and passage 6 (now required for the conventional non-locking, non-mortice closure, as already described) to receive the novel locking non-mortice closure of the preferred form of my invention (except for a simple drilled passage for a safety or emergency unlocking provision, required by some State laws, and which will be 65 fully described hereinafter).

I am able to accomplish these and other results by associating the locking means directly with the latch bolt of the closure device. Within the rose plate 18 fastened to the inner or right side of the door, Figure 5 (the plate is preferably

a metal stamping, providing a hollow space or cavity as shown) is an inner plate 30 of circular outline—see Figures 3, 4 and 5. Inner plate 30 may be secured to, or form part of, rose plate 18 or it may be secured directly to the door, the latter fastening being shown (screws 31) in the illustrative figures.

It will be observed from Figures 3, 4 and 5, that inner plate 30 is provided with holes 34, through which pass the screws 14, which secure 10 the rose plate to the door. Inner plate 30 is formed to provide a trackway or slideway 32—see especially Figures 3 and 4—for a pair of slide elements 33. Pivoted to the inner plate at 35a is a pair of lever arms 35, each provided with a 15 slot 35s, in which is received a pin 33p, provided on the said pair of slides 33. A tensile spring 36 is provided between, and attached to, the pair of levers 35, due to which the two levers are urged to approach each other (as shown in Figure 20 3). The two said slots 35s on levers 35 are oriented as shown in Figures 3 and 4, so that the tendency of the two levers to approach each other—due to spring 36 just described—is communicated to the slides 33, which likewise are 25 normally urged by the spring 36 to approach each other.

The inner edges of the pair of slides 33, i. e. the edges which approach each other, are provided with notches or cut-outs 39 which embrace 30 the square knob spindle 19, when the pair of slides are in approaching position, as shown in Figure 3. Hence in the position of the parts shown in Figure 3, with the pair of levers and the pair of slides in approaching position, the 35 spindle 19 will be held between the slide cut outs 39 in locked position.

Provided between the distal ends of lever arms 35 is a cam element 45 generally of the shape shown in Figures 3 and 4, having a long axis 40 (vertically oriented in Figure 3) and a short axis normal thereto. In the position shown in Figure 3, with the short axis of cam element 45 placed between the distal ends of levers 35, the said levers and the pair of slides are in approaching position, with the knob spindle locked between the slides. By turning cam element 45 from locking position (Figure 3) 90° to the position shown in Figure 4, with the long axis of the cam between the distal ends of levers 35, both the levers and 50 the slides 33 are spread apart, to unlock knob spindle 19. To permit this turning of cam element 45, inner plate 30 is provided with a circular hole 37 for a hub member 47, Figure 5, to which the cam 45 is secured (or made integral 55 with). Hub 47 is provided with a square hole 47h, through which is passed square spindle 40, which extends through an opening 18s in inner rose plate 18; to the end of spindle 40, projecting at the inner side of the door, is secured a thumb 60 turn or finger lever 41.

Thumb turn 41 is secured onto spindle 40 so as to be oriented 90° or normal with the long axis of the cam element 45. Hence, when the thumb turn is in vertical position—which is its normal 65 position—shown in Figure 2, the long axis of the cam will be horizontally oriented as in Figure 4, spreading the levers and the slides apart and unlocking the knob spindle 19. By turning 40 to the horizontal (the position shown in dot and dash 70 lines in Figure 2) the cam element 45 is turned 90° to present its narrow axis between the pair of levers 35, thus permitting tensile spring 36 to bring the slides 33 together and to lock the knob spindle 19.

The door handle 17 may be in the form of a knob as shown, or it may be in the form of a lever handle. In either form, the locking thumb turn or finger lever 41 is so placed relative thereto that simultaneously with the grasping of the door knob, one finger of the hand (e. g. the index finger, as shown in Figure 1) may be used for operating the lock 41.

The hub 47 may be further provided with a flange 48 having a 90° cut-out portion 48c, Figures 3 and 4, within the confines of which is a pin 38 projecting from the plate 30. Pin 38 serves to stop the turning of the thumb turn 41 and associated parts in locking position (Figure 3) by abutting against one shoulder of the recess 48c and in unlocking position (Figure 4) by abutting against the other shoulder.

The inner surfaces of the pair of lever arms 35 are provided near their distal ends with slight depressions 35d, Figures 3 and 4, within which the ends 45e of the cam element 45 snap—see Figure 4—to maintain the long axis of the cam in a horizontal position and the lever arms and slides spread apart and knob spindle 19 unlocked.

25 In some States, cities and countries, ordinances have been enacted requiring door locking devices of the class described to be provided with means for opening the door from the outside, by the use of a special tool or screw driver or the like. 30 The locking device of this invention may be readily provided with this required safety opening means.

As shown in Figure 5, the locking spindle 40 extends almost to the outlet or left face 10L of the door and is provided at that end with a slot 51 for receiving the bevel end of a screw driver 50, the rose plate 18' provided on the outer side of the door being provided with an opening 18's for the screw driver. The door is simply drilled, 40 Figure 5, to provide clearance through the door for spindle 40.

It will thus be observed that my invention makes it possible to quickly and facilely associate with simple latching bolt closures of the bath room 45 lock type or the like, a locking device of novel and efficient construction, which is economical to manufacture.

It will also be observed that while I have illustrated my invention as particularly applicable to non-mortice type locks, my device may be installed and associated with other forms of closures, operable by a rotary spindle and that the illustration therefor is for purposes of exemplification; and that while all of the associated parts, 50 as exemplified, provide a form of the associated parts found to give desirable results, some of the described features may be obtained by using selected portions of the assembly illustrated. Accordingly, the illustration is not to be considered 55 as limiting in character but that my invention is intended to be outlined within the scope of the appended claims.

Having thus described my invention and illustrated its use, what I claim as new and desire to 60 secure by Letters Patent, is—

1. In a latch spindle fastener of the character normally provided with simple rose plates, the combination with the spindle thereof comprising means to prevent its rotation and capable of replacing either of said rose plates, comprising a separate plate assembly carrying said locking means and attachable independently of said latch bolt and a manipulative member for controlling the said means comprising a rotary shaft having 70 a portion thereof extending partially in close

proximity towards one of said rose plates and extending through the other and accessible from both sides of said door, the said means on said plate includes a pair of spaced slides each of which is notched to embrace the said spindle and 5 wherein the said manipulative member includes a lever for adjusting the said pair of slides to and from each other.

2. In a latch spindle fastener of the character normally provided with simple rose plates, the 10 combination with the spindle thereof comprising means to prevent its rotation and capable of replacing either of said rose plates, comprising a separate plate assembly carrying said locking means and attachable independently of said latch bolt and a manipulative member for controlling the said means comprising a rotary shaft having a portion thereof extending partially in close proximity towards one of said rose plates and extending through the other and accessible from 20 both sides of said door, the said locking means and the said manipulative member include a pair of slides notched to embrace the said spindle, a pair of lever arms connected to the said slides, and a cam element positioned between the distal 25 ends of the said lever arms and said cam element being connected to, and actuated by the said manipulative member to control the position of the said pair of slides.

3. In a latch spindle fastener having a spindle 30 and a latch bolt operatively connected thereto, the combination of a pair of slides notched to engage and lock the said spindle, each provided with a pin, a pair of lever arms provided with slots for the pins of the respective slides, and a 35 tensile spring stretched between the distal ends of the said pair of levers whereby said pair of slides are urged to approach each other and to lock the said spindle.

4. In a latch spindle fastener having a spindle 40 and a latch bolt operatively connected thereto, the combination of a pair of slides notched to engage and lock the said spindle, each provided with a pin, a pair of lever arms provided with slots for the pins of the respective slides, a tensile 45 spring stretched between the distal ends of the said pair of levers whereby the said pair of slides are urged to approach each other and to lock the said spindle, and a cam element positioned between the distal ends of the said pair of levers 50 and having a short axis ineffective to spread the levers apart and a long axis effective to spread the levers apart whereby the said slides are spread apart to unlock the said spindle.

5. The combination according to claim 4 wherein the said lever arms are provided with depressions into which the ends of the said cam element on its long axis snap to hold the said pairs of lever arms and slides spread apart in non-locking position.

6. The combination according to claim 4 wherein the closure fastener is provided with a pair of rose plates, further provided with a manipulative member mounted on the inner rose plate, a spindle to which the said manipulative member and the said cam element are secured, the end of the said spindle extending towards the outer side of the door and confined within its thickness, the end of said spindle being provided with a key receiving end, the outer rose plate being 70 provided with an opening for a keying member to fit said key receiving end.

7. In a latch spindle fastener, the combination comprising spaced rose plates in which spindle operating knobs are arranged to have rotary bear- 75

ings, a spindle locking assembly plate arranged to be housed within one of said rose plates, said locking assembly plate carrying spindle engaging means comprising a pair of resiliently joined plates each notched to engage said spindle and a rotary element for operating said means and adjusting the same into locking and unlocking position, a manually operative member having a bearing in one of said rose plates and having a portion keyed to said rotary element for positive

rotation thereof adjacent one face of said rose plate, said rotary element being arranged to be accessible on the opposite face by other keying means extended through an orifice in the other rose plate, whereby normally the rotary element is operable only by said member but may be operated by said keying means through the orifice of the last mentioned rose plate.

MORRIS FALK. 10
